UNITED STATES PATENT OFFICE.

ALFRED R. DORROH, OF WASHINGTON, DISTRICT OF COLUMBIA.

WASHING DEVICE.

Application filed November 1, 1924. Serial No. 747,293.

My present invention pertains to apparatus for washing clothes, articles of textile material and other fabric articles; and it contemplates the provision of a simple and efficient device through the medium of which clothes may be expeditiously and thoroughly cleansed in a bath tub, wash tub or any other convenient receptacle.

To the attainment of the foregoing, the invention consists in the improvement as hereinafter described and definitely claimed.

In the accompanying drawings, forming part of this specification:—

Figure 1 is a front elevation of the device 10 constituting the preferred embodiment of my invention.

Figure 2 is an edge elevation of the same.

Figure 3 is an enlarged broken fragmentary section taken in the plane indicated by 20 the line 3—3 of Figure 2 and showing the mechanism for twisting the clothes container about its axis.

Figure 4 is an enlarged detail section taken on the line 4—4 of Figure 1.

Figure 5 is a detail perspective showing the clothes container of the device, per se.

Similar numerals of reference designate corresponding parts in all of the views of the drawings.

The present and preferred embodiment of my invention is in the form of a device adapted to be placed in and removed from a bath tub or any other receptacle in which it is desired to wash clothes or other articles.

I desire it distinctly understood, however, that my invention is not restricted to a device separable from a receptacle inasmuch as without involving departure from the scope of my claimed invention the device 35 may be permanently associated with a tub or other receptacle.

As illustrated the preferred embodiment of the invention comprises a frame 1, a clothes container 2, a holder for said container, said holder being generally designated by 3 and being movable in the frame, and means for twisting said container about its axis incident to movement of the container in the frame.

The frame may be of any construction 50 compatible with the purpose of my invention though I prefer to have it comprise a base 4 on which are pads or feet 5, a crown bar 6 and series of uprights arranged adjacent to each end of the base 4 and crown bar 6 and fixed to and joining the said base 4

and crown bar 6. Two of the uprights adjacent one end of the device are designated by 7 and are provided with racks 8. The two bars opposite the said bars 7 and numbered 9 are smooth or plain. Adjacent to the opposite end of the device are two bars 7^a which bear racks 8^a, and two plain bars 9^a, said plain bars 9^a being arranged opposite the rack sides of the bars 7^a. It will 60 also be noted by comparison of Figures 1, 2 and 3 that the rack bars 7, are arranged adjacent to the back of the device while the rack bars 7^a are arranged adjacent to the front of the device for a purpose hereinafter 70 set forth.

The holder 3 includes a bar 10 that extends through and is movable in an opening 11 in the crown bar 6. The said bar 10 is shown as provided with a hand grasp 12, 75 and in this connection I would have it understood that the holder 3 may be reciprocated by the direct application of the hand to the hand grasp 12 without affecting my invention. I show the bar 10, however, as 80 equipped with a rack 13 which rack is meshed with a spur gear 14 on a shaft 15, journaled in appropriate bearings on the frame 1 and carrying a crank 16. When this latter mechanism is employed it will be 85 manifest that rotation of the crank 16 first in one direction and then in the other will be attended by reciprocation of the holder 3 in the frame 1. When the meshed rack 13 and gear 14 are employed, I prefer to equip 90 the crown bar 6 with anti-friction rollers 16^a, Figure 4, so as to ease the movements of the bar 10 in opposite directions.

In addition to the bar 10 the holder 3 comprises arms 17 which extend in opposite directions from the lower end of the bar 10 and are preferably curved as designated by 18 in Figure 2 and terminate in sleeves 19. Journaled in the said sleeves 19 are rotor shafts 20 and 21 which have support gears 22 at their ends. It will also be understood by reference to Figure 3 that the gears 22 of the rotor shaft 20 are meshed with the racks 8 of the bar 7 while the gears of the rotor shaft 21 are meshed with the racks of the bars 7^a. From this it follows that the rotors will be synchronously rotated in opposite directions incident to movement of the holder 3 in the direction of the length of the frame 1.

The container 2 of my improvement is 110 shown as formed of flexible material with

interstices for the passage of water, into and out of the container, and the container is also shown as provided with a closure flap 30, said flap 30 being designed to be closed after clothes, designated by 31 in Figure 5, are placed in the container. The rotors formed by the shafts and gears described are provided at their inner ends with broad extensions 32, and on the said extensions 32 10 are preferably secured in detachable manner heads 33 connected as shown or in any other approved manner to the ends of the container 30. Manifestly when the holder 3 is moved upwardly or downwardly in the 15 frame 1, the container 2 will be twisted first in one direction and then in the other. When this is done while the container 2 is immersed in a body of water it will be noted that the effect of twisting the container 2 20 first in one direction and then in the other will be to throw water into and expel water from the container 2 with the result that the clothes in the said container 2 will be expeditiously and thoroughly cleansed.

25 In the practical use of my novel device, clothes or the like are placed in the container 2, and the flap of the container is closed, after which the device is placed in a receptacle containing water and the holder 3 30 is reciprocated in the frame 1. When this is done the container 2 will be moved and will be twisted in the manner and for the purpose set forth.

I have specifically described the construction and relative arrangement of the parts embraced in the present and preferred embodiment of my invention in order to impart a definite understanding of the said embodiment. I do not desire, however, to be understood as confining myself to the structure disclosed, my invention being defined by my appended claims within the scope of which structural changes may be made without affecting my invention or involving departure 45 from the same.

Having described my invention, what I claim and desire to secure by Letters Patent, is:—

1. The combination in a washing device, 50 of a frame, an open work twistable clothes container, a container holder movable in the frame, racks carried by the frame, and rotors journaled in the holder and connected to the ends of the container and having spur 55 gears meshed with the racks, the racks adjacent to opposite ends of the container being reversely arranged whereby on movement of the holder relative to the frame the

rotors will be synchronously rotated in opposite directions. 60

2. In a washing device, the combination of a frame, spaced rotors having gears, a twistable clothes container interposed between and connected to said rotors, a rack carried by the frame and arranged at one side of the gear of one rotor and meshed with said gear, a second rack carried by the frame and meshed with the gear of the other rotor and arranged at the opposite side of said gear, with reference to the first-named 65 rack, a holder connected with and adapted to move the said rotors in the frame, the said holder having a bar guided in the frame and formed with a rack, a shaft journaled in the frame, and a spur gear on the shaft meshing 70 with the rack of the bar.

3. The combination in a washing device of a frame having spaced groups of upright bars, the rear bars of one group bearing racks and the front bars of the other group bearing racks, rotors one to each group of bars and having spur gears meshed with the racks of certain of the bars, a twistable clothes container interposed between and connected with said rotors, and a reciprocatory holder movable in the frame and connected to the said rotors, whereby to rotate the rotors in opposite directions. 85

4. In a washing device, the combination of a frame, spaced rotors having gears formed on the ends thereof, a twistable clothes container interposed between and secured to said rotors for movement therewith, racks included in one side of the frame and adapted to receive the gears of one of 90 said rotors, racks also included in the other side of said frame and meshed with the gears of the other rotor, said racks being reversibly disposed, and a holder connected with and adapted to move said rotors whereby the 95 gears will rotate the latter in opposite directions for twisting the clothes container. 100

5. In a washing device, a frame, a twistable clothes container, a holder for said container and being mounted for reciprocatory vertical movement longitudinally of said frame, means including racks in said frame, a rack at each end of the frame, said racks having teeth facing one another and gears carried by the holder and meshing with said 105 racks to twist said container in opposite directions upon movement thereof in both its upward and downward direction incident to the movement of said holder in the frame.

In testimony whereof I affix my signature.
ALFRED R. DORROH.
